PLATE HARDWARE

Raymond U. H. Tegner, Rockford, Ill., assignor to
Amerock Corporation, Rockford, Ill.

Filed Jan. 10, 1972, Ser. No. 216,871

Term of patent 14 years

Int. Cl. D13—03; D8—99

U.S. Cl. D8—179

FIG. 7.

FIG. 8.

FIG. 9.

FIG. 10.

FIG. 1 is a front view of a plate hardware item incorporating my new design and embodied in a single switch plate.

FIG. 2 is a side view of the switch plate.

FIG. 3 is a sectional view taken along the line 3-3 in FIG. 1.

FIG. 4 is a front view of a plate hardware item incorporating my new design and embodied in a receptacle plate, the surface texture extending around the entire plate as in FIG. 1.

FIG. 5 is a side view of the receptacle plate.

FIG. 6 is a sectional view taken along the line 6-6 in FIG. 4.

FIG. 7 is a front view of a plate hardware item incorporating my new design and embodied in a combination switch and receptacle plate, the surface texture being applied around the entire plate as in FIG. 1.

FIG. 8 is a bottom view of the plate shown in FIG. 7.

FIG. 9 is a front view of a plate hardware item incorporating my new design and embodied in a triple switch plate, the surface texture extending around the entire plate as in FIG. 1.

FIG. 10 is a bottom view of the plate shown in FIG. 9.

FIG. 11 is a front view of a plate hardware item incorporating my new design and embodied in an escutcheon

plate for a door knob, the surface texture extending around the entire plate as in FIG. 1.

FIG. 12 is a side view of the plate shown in FIG. 11.

FIG. 13 is a sectional view taken along the line 13-13 in FIG. 11.

FIG. 14 is a front view of a plate hardware item incorporating my new design and embodied in a plate for supporting a tissue holder.

FIG. 15 is a front view of the plate shown in FIG. 14 and taken along the line 15-15 in FIG. 14, the surface texture extending around the entire plate as in FIG. 1.

FIG. 16 is a sectional view taken along the line 16-16 in FIG. 15.

The portions shown in broken lines form no part of the design.

I claim:

The ornamental design for plate hardware, as shown and described.
